UNITED STATES PATENT OFFICE.

CONSTANT J. KRYZANOWSKY, OF MOUNT WASHINGTON, MARYLAND, ASSIGNOR TO THE CROWN CORK AND SEAL COMPANY OF BALTIMORE CITY, OF BALTIMORE, MARYLAND, A CORPORATION OF MARYLAND.

OPENER.

1,393,029.

Specification of Letters Patent. Patented Oct. 11, 1921.

Application filed May 18, 1917. Serial No. 169,424.

To all whom it may concern:

Be it known that I, CONSTANT J. KRYZANOWSKY, a citizen of the United States, residing at Mount Washington, county of 5 Baltimore, and State of Maryland, have invented certain new and useful Improvements in Openers, fully described and represented in the following specification and the accompanying drawings, forming a part of the 10 same.

This invention relates to improvements in bottle-openers and particularly to that class of cap-removing devices which are secured to a support.

15 Bottle-openers of this sort, as heretofore known, are subject to the disadvantage that they require careful and accurate positioning of the capped bottle-head; and further they require installation in a particular given position. There has been found, too, the additional objection that they tend, by virtue of 20 their practically rigid character, to cause breakage of the bottle in case the first and comparatively slight force exerted thereon 25 fails to remove the cap.

It is the object of the present invention to provide a stationary bottle-opener that obviates the necessity of careful and accurate 30 positioning of the bottle; one that may be secured to a support in any position; one that practically eliminates the danger of breakage; and one that is, withal, simple in its construction and economical to manufacture.

35 A preferred form of bottle-opener constructed in accordance with this invention is described in the following specification and illustrated in the accompanying drawing, it being understood that changes may be made 40 in the form, construction and arrangement of the parts without departing from the invention.

In the drawing—

45 Figure 1 is a perspective view of a bottle-opener constructed in accordance with the invention;

Fig. 2 is a plan view of the opener secured to a support;

Fig. 3 is a front view of the opener;

50 Fig. 4 is a central cross-sectional view of the opener secured to a support, showing a

bottle in place, ready for the removal of the cap; and

Fig. 5 is a plan view (reduced) of the blank from which the opener is formed. 55

The opener comprises a bearer against which the top of the cap to be removed is forced and a remover for engaging the edge of the cap skirt. These elements may be constructed in a variety of ways, but in the preferred form shown they consist of two long flat bars 6 and 7, the opposite edges of 60 which are parallel and are separated, with reference to a right line, by a space less than the diameter of the caps 11 to be removed. 65 One of these bars, the one, for example, marked 7, is offset inwardly to lie in a plane parallel to the plane of the bar 6, and the distance throughout which the offset relation extends is substantially greater than the diameter of the cap to be removed. For example, in the opener illustrated in the drawing, the bar 7 is offset from the bar 6 throughout a distance upward of three times 70 the diameter of the cap. 75

The device is constructed to be secured to a stationary support, as, for example, the edge of a bar. The securing means may be of a variety of constructions. In the preferred form shown, the flat bars which constitute the bearer and remover are continued around rearwardly to parallel themselves and form two securing base portions 9 provided with screw holes 10 for screws 11, by means of which the device is secured to the stationary support 12. The base portions 9 are spaced from the bearer and remover, so that the latter are supported a substantial distance out from the bar or other fixture. 85

In the preferred form the entire device is 90 formed from a flat blank of the configuration shown in Fig. 5. This blank is a pressing formed from suitable material, preferably spring steel, and is slotted longitudinally, as clearly appears in the drawing, the width of the slot being the distance separating the edges of the bars 6 and 7, as above described. The screw holes 10 are formed near the ends of the blank and the parallel edges of the slot are beveled, as shown at 13, 100 Fig. 5, one edge being beveled on one side of the blank, the other edge on the other side. 95

The blank is placed in a suitable machine and the ends are turned up and bent over parallel to the main portion of the blank until the curved end edges are separated by a small space, as shown in Figs. 1 to 3, thus forming the rear supporting base portions 9, and leaving the long flat bars, which constitute the bearer and remover, spaced out from the same. During this operation, one of these bars, for example the one marked 7, is bent inwardly, so that a considerable portion thereof—a portion substantially greater in extent than the diameter of the caps—is made to lie in a plane offset from the plane of the other bar 6, and parallel thereto, this construction clearly appearing in Fig. 2. The device after suitable finishing is ready to be secured to the stationary support 12 by means of screws 11 passing through the holes 10, and it may be placed either in vertical position, as shown in Fig. 4, or in horizontal position, or, if desired, at any intermediate angle.

In operation, the bottle 14, sealed by a crown cap 8, is advanced head on toward the device until a portion of the top of the cap is forced against the upper portion of offset bar, or bearer 7, as shown in Fig. 4. By slight manipulation, the position of the bottle is adjusted so that the lower beveled edge of the other bar 6, the remover, is engaged by the edge of the cap skirt. A downward pivotal movement of the bottle as it is held against the bearer 7, will cause the cap to be forced off by the remover 6.

The extent of the distance throughout which bearer and remover 6 are offset from each other is several times greater than the diameter of the caps to be removed, and it will be seen that the relation between these two elements is constant between the terminal points of the offset portion. Consequently, within this range it makes no difference at what point the bottle is presented for removal of the cap, as the removal may be effected at any point. As a result of the construction described, there is no necessity for accurate and careful positioning of the bottle, and the cap-removing operation is readily and quickly carried out. Furthermore, the effective extent of the cap-engaging parts is such that, when desired, a plurality of bottles may be accommodated simultaneously, as, for example, when a dispenser presents two bottles, one in each hand, at the same time.

It is not essential that the offset bar be the lower one, as shown in Fig. 4, although this is the preferred arrangement, inasmuch as the mouth of the bottle upon being opened will be pointed upward, thereby preventing the contents from spilling out. Further, it is not essential that the bottle be presented in the manner shown, as, if desired, it may be placed so that the edge of the bar 6 serves

as the bearer against which the top of the cap is forced, the edge of the offset bar 7 engaging the edge of the cap skirt, and thus serving as the remover. Regardless, however, of the particular manner of presenting the cap for removal, the feature of the effective extent of bearer and remover being several times greater than the diameter of the cap, makes it unnecessary for an accurate positioning of the bottle, and the removal is always easily and quickly accomplished.

As the bearer and remover are not rigid, in case the first and comparatively slight force exerted on the bottle fails to remove the cap, as may occasionally happen, the parts will yield sufficiently to prevent the breakage that might ensue if the capped bottle were in contact with rigid members.

In conclusion, it will be seen that, in addition to the structural advantages already pointed out, this opener is extremely simple and, owing to its simplicity and the fact that it is fashioned from a flat blank, it adds to the advantage of readiness and effectiveness in use, the further advantage of economy in manufacture.

What is claimed is:

1. As a new article of manufacture, a device for removing crown caps from bottles and the like, comprising a pair of bars constituting a bearer against which the top of the cap to be removed is forced and a remover for engaging the top of the cap skirt and having their opposing edges separated by a distance less than the diameter of the cap, said bars being in substantially the same plane near the ends thereof, one of said bars being offset from the other throughout an extent substantially greater than the diameter of the cap, said bars being continued around rearwardly to form means whereby the device may be attached to a support.

2. As a new article of manufacture, a device for removing crown caps from bottles and the like, formed from a flat blank and comprising a pair of bars constituting a bearer and a remover and having their opposing edges separated by a distance less than the diameter of the cap to be removed, said bars being in substantially the same plane near the ends thereof, one of said bars being offset from the other throughout an extent substantially greater than the diameter of the cap, and said bars being continued around rearwardly to form means whereby the device may be attached to a support.

3. As a new article of manufacture, a flat blank slotted to form a bearer against which the tops of caps to be removed from bottles are forced and a remover for engaging the edges of the cap skirts, the effective extent of said bearer and remover being substantially greater than the diameter of the caps,

the blank having its ends bent back on itself to form supporting wings for securing the whole to a support with the bearer and remover spaced a substantial distance therefrom.

4. As a new article of manufacture, a device for removing crown caps from bottles and the like, comprising a pair of parallel bars having at their ends supporting wing portions offset therefrom and parallel thereto, one of said bars having a portion offset

from the other bar throughout an extent greater than the diameter of a cap, one of said bars constituting a bearer against which the top of the cap to be removed is forced, 15 the other bar constituting a remover for engaging the edge of the cap skirt.

In testimony whereof, I have hereunto set my hand.

CONSTANT J. KRYZANOWSKY.

Witness:

D. HAYES PAGE.
